CURLER COMB

Siegfried Behr, Flushing, N. Y., assignor to Ben Hur Products, Inc., New York, N. Y., a corporation of New York

Application April 27, 1939, Serial No. 270,394

4 Claims. (Cl. 132—19)

This invention relates to combs and particularly to combs which are adapted to be carried by ladies in their hand-bags for which purpose the combs must be of relatively small size.

It is an object of the present invention to provide a comb of that type and one which in addition is combined with an instrument for facilitating the curling of the hair and which still is small enough to be carried in a ladies' hand-bag and which is light and may be easily operated.

With these and other objects in view which will appear more clearly as the description progresses, the invention consists in the novel construction, adaptation and arrangement and combination of parts hereinafter described and illustrated in the accompanying drawing, in which

Fig. 1 is a top plan view of the improved comb-curler.

Fig. 2 is a side view thereof with the curler bars in operative position.

Fig. 3 is a side view of the comb with the curler bars in closed position thereon.

Fig. 4 is a detail sectional view on an enlarged scale taken on the line 4—4 of Fig. 2.

Fig. 5 is a detail sectional view on the line 5—5 of Fig. 3.

Fig. 6 is a detail view showing the pivot joint of the curler part on the comb looking in the direction of the arrow 6—6 of Fig. 4.

Fig. 7 is a detail view in the direction of arrows 7—7 of Fig. 4.

Fig. 8 is an exploded detail section on the line 8—8 of Fig. 4.

Fig. 9 is a vertical section on the line 9—9 of Fig. 2.

Referring to the drawing 10 is a comb, preferably of moldable plastic material such as acetate, plastic or the like. It consists of a back portion 10a which has a horizontal longitudinal top line and a lower longitudinal line slightly inclined thereto so that the back portion 10a is wider at one end than at the other but its thickness is equal between these lines. From the lower limit line, a plurality of teeth 11 which are integral with the back 10a extend downwardly, parallel to each other and all have their ends on a line parallel to the top horizontal line of the back 10a which makes the teeth of gradually and uniformly increasing length as shown from right to left in Fig. 2. As shown in Figs. 1 and 2, the back 10a of the comb extends on the right side tapering a distance beyond the end tooth 11a of the comb as can be seen in Fig. 1 and by the dotted line indicating the end of extension 10a in Fig.

2. Against both faces of back 10a lean the curler plates 12a which form the rear portions of curler bars 12 and pivotally attached to back 10a by means of a pivot pin or eyelet 13. Each of the curler plates has a cylindrical projection 14 and 14a surrounding the central aperture for pivot 13 and extending into comb portion 10a through a portion of its thickness. Cylinder 14 is provided with a horizontal slot 14b while cylinder 14a is provided with a horizontal bar 14c on its 10 face which fits closely into the slot of 14b. The inner faces of plates 12a are each provided with two small recesses 15 which engage complementary projections 15a on comb-back 10a. These projections and recesses are preferably 15 located on the line of the longitudinal axis of bars 12 when in fully closed and open positions and a short distance from pivot 13 and adapted to snap into and out of the recesses when said bars 12 are rotated on pivot 13, the resiliency of 20 the material of which the comb 10, curler bars 12 and curler plates 12a are made permitting this action, while the slot 14b and projecting bar 14c lock plates 12a together for uniform simultaneous rotation, while the projecting heads 15a 25 arrest the rotation when the bars are in open and closed positions on the comb. The shape of the curler bars 12 as shown in Fig. 9 in section is approximately semicircular so that together they have the form of a longitudinally 30 slotted cylinder, slightly tapered in which form they are held, by the pivotal joint above described, in any angular position.

When the curler bars 12 are closed as shown in Fig. 3, the comb may easily be accommodated 35 in a lady's hand bag and conveniently used as a comb. When the lady desires to curl her locks, she will first straighten a strand of hair using the comb, then open the curler bars as shown in Figs. 1 and 2, and shift the strand of hair into 40 the slot between the bars, turn the comb and roll up the hair on the curler bars and finally place a bobby pin alongside the bars on the curled hair to hold the curl from unwinding.

It is thought to be clear that the simple construction of the device herein described provides a very simple and very useful device for combing and curling the hair which can be manufactured and sold at a very reasonable price and conveniently be used because of its simplicity.

Changes in details of construction may be made without departing from the invention and I therefore desire to be limited only by the state of the prior art and the appended claims.

I claim:

1. A comb having at one end a pair of elongated bars pivotally connected thereto on opposite sides, said bars being held on opposite sides of said comb and connected by a common pivot to move simultaneously through equal angles.
2. A comb having at one end a pair of elongated bars of semi-circular section pivotally connected thereto on opposite sides forming a practically cylindrical structure, said bars being joined to each other to move simultaneously through equal angles and means to limit the movement of said bars and to hold them automatically at fixed end positions.
3. A comb comprising a flat back portion and teeth extending therefrom parallel to each other, said back portion having an enlarged portion at one end with an aperture therein, a pair of semi-cylindrical bars, one on each side of said back portion, each bar having a cylindrical boss thereon lodged in the aperture of said back portion, a pivot pin passing through said bosses for joining said bars to said comb permitting rotary movement thereon, a projection on the face of one boss engaging a recess in the other boss joining said bars for simultaneous rotary motion on said pivot pin.
4. A comb comprising a back portion, teeth depending from said back portion, a pair of spaced bars pivotally connected to one end of said back portion and forming an extension thereof, said bars being adapted to be collapsed over said back portion, means for holding the bars in fixed extended position and means for holding the bars in fixed collapsed position.
